PORATION OF DELAWARE.

FUEL-RESERVE-SUPPLY SYSTEM.

1,419,373.

Specification of Letters Patent. Patented June 13, 1922.

Application filed November 18, 1918. Serial No. 262,995.

To all whom it may concern:

Be it known that we, CHARLES F. GREEN and HARRY W. LINDSEY, Jr., residing at Defiance, county of Defiance, State of Ohio, and Toledo, county of Lucas, State of Ohio, respectively, have invented certain new and useful Improvements in Fuel-Reserve-Supply Systems, of which we declare the following to be a full, clear, and exact description.

10 Our invention relates to improvements in fuel reserve supply systems for use particularly in connection with the source from which the fuel is supplied to the engine of motor driven vehicles and has for its object 15 to provide simple and inexpensive means by which the reserve supply is maintained.

A further object of the invention is to provide improved means connecting the fuel supply source with the manifold or carburetor of the engine which will permit the consumption of a predetermined amount of fuel, after which the driver's attention is called to the fact that only the reserve supply or predetermined amount of the main supply 25 remains.

A further object of the invention is to provide a partitioned fuel holding receptacle or adjacent receptacles into which project conduits having means for automatically effecting their opening and closing when shifted from one position of adjustment to another in connection with a suction producing apparatus for drawing the fuel from the receptacle through said conduit.

35 A still further object of the invention is to provide a plurality of suction conduits adapted to project into separate liquid holding compartments with means for alternately raising and lowering said conduits in said 40 compartments and means for effecting the alternate opening and closing of the conduits when raised and lowered.

To these and other ends the invention comprises certain novel features of construction 45 and arrangement of parts as will be herein-after more fully pointed out, it being understood that various changes may be made in the manner of constructing and operating the apparatus without departing from the 50 spirit of the invention.

A structure illustrating one embodiment of our invention is shown in the accompany-

ing drawings forming part of the specification in which:

Figure I is a diagrammatic view partly in section illustrating the preferred embodiment of the invention.

Figure II is a fragmentary sectional elevation through the fuel supply tank illustrating the manner of mounting the suction conduits therein.

Figure III is an enlarged fragmentary sectional view showing the manner of constructing and mounting the valves for alternately opening and closing the suction conduits.

Figure IV is a fragmentary sectional plan showing the operating mechanism for perfecting the raising and lowering of the conduits, and

Figure V is a sectional plan view on the line 5—5 of Figure II.

Like letters of reference indicate like parts in the several views in the drawings.

Referring to the drawing, 10 represents any preferred type of engine suitable for motor driven vehicles, the carburetor and manifold thereof being indicated at 11 and 12 respectively. A vacuum gravity feed tank 13 of any well known design is connected with the carburetor and manifold of the engine by 80 means of the conduits 14 and 15 respectively as shown in Figure I, the vacuum tank being also connected with the separate fuel compartments 16 and 17 of the supply tank 18 by means of the conduits 19 and 20 respectively. The compartments 16 and 17 are formed preferably by providing the partition 21 in the tank 18 but may be formed by placing together separate tanks or liquid holding receptacles. As shown in Figure III the conduits 19 and 20 project into the tank upon opposite sides of the partition to points adjacent the bottom of the tank. The conduits at their lower extremities are provided with the valve housings 22 which are preferably 90 screwed upon the conduits and have in their lower ends the fuel inlet openings 23 adapted to be alternately opened and closed by the valves 24 on the stems 25 which project downwardly from the housings as shown in Fig. III. The stems 25 at their lower ends are provided with heads 26 upon which rest the spring seats 27 for supporting the lower ends of the springs 28, the upper ends of

which are seated upon the valve housings or casings 22 as clearly shown in Figure III.

It will be readily seen that the springs retain the valves in closed position as long as the stems are out of contact with the bottom of the tank which co-operates with said stems to open the valves when the conduits are lowered a predetermined amount.

Upon the top of the tank is provided a plate 29 having a post or standard 30 which is recessed at 31 to receive a spring 32 yieldingly engaging the head 33 of a bolt 34 carrying an operating member having a handle 35 and oppositely extending arms 36 projecting loosely into recesses 37 of the lugs or collars 38 secured upon the conduits 19 and 20 as shown in Figure II.

The conduits which are slidably mounted in or guided by the plate 29 may be alternately raised and lowered by shifting the lever or pivoted operating member from one position of adjustment to another.

In order that said pivotal member may be held in either of its two positions of adjustment to prevent the accidental shifting of the conduits within the tank we have provided upon the standard 30 the cam or inclined surface 39 at the opposite sides of which are the recesses 40 in one or the other of which the lug or projection 41 on the operating lever normally rests, it being understood that the spring 32 will yieldingly hold the lever in engagement with the standard and prevent the accidental displacement of the same and consequently of said conduits for the reason that the lug will have to ride over the cam and compress said spring before such displacement can occur.

In the operation of our fuel reserve supply apparatus at the time the engine is stopped by reason of the fact that all of the fuel has been used out of the compartment into which the open conduit is projected, the driver is only required to shift the position of the operating lever for the purpose of lowering the opposite conduit at which time the valve thereof will automatically open while the valve of the other conduit will automatically close to prevent the suction of air therethrough. By this means the driver is not required to reset the device when a new supply of fuel is placed in the fuel holding compartments as the main supply may be drawn from either of said compartments.

Having thus described our invention, what we claim as new and desire to secure by Letters Patent is:

1. A device of the class described, comprising a plurality of liquid holding receptacles, a conduit extending into each of said receptacles, and means for lowering said conduits selectively.

2. A device of the class described, comprising a plurality of liquid holding recep-

tacles, a conduit extending into each of said receptacles, means for simultaneously raising one and lowering the other of said conduits, and means for automatically opening and closing each of said conduits when raised and lowered.

3. A device of the class described, comprising a liquid holding tank having a partition therein, conduits extending into said tank on the opposite sides of said partition, and a lever operatively connected with said conduits for simultaneously moving the same in opposite directions.

4. A device of the class described, comprising a liquid holding tank having a partition therein, conduits extending into the tank on opposite sides of the partition, a lever operatively connected with said conduits for simultaneously moving the same in opposite directions, and spring controlled valves for automatically opening and closing each of said conduits when raised and lowered.

5. A device of the class described, comprising a liquid holding tank having a partition therein, conduits extending into the tank upon opposite sides of the partition, a member having oppositely extending arms, each of which is operatively connected with one of said conduits, said member being pivoted intermediate the ends of its arms and adapted to be shifted upon its pivot for the purpose of alternately raising and lowering said conduits, and means for automatically closing each of said conduits when raised and opening the same when lowered.

6. A device of the class described, comprising a liquid holding tank having a partition therein, a pair of movable conduits extending into the tank on opposite sides of the partition, means for alternately raising and lowering said conduits, and means for automatically closing each of said conduits when raised and opening the same when lowered.

7. A device of the class described, comprising a liquid holding tank having a partition therein, a pair of movable conduits extending into the tank on opposite sides of the partition, recessed members carried by each of said conduits, a pivotally mounted member having its ends extending loosely into said recesses and provided with a laterally extending handle adapted when moved in opposite directions to alternately raise and lower said conduits, and means for automatically closing each of said conduits when raised and opening the same when lowered.

8. A device of the class described, comprising a liquid holding tank, a partition therein, a pair of movable conduits extending into the tank on opposite sides of the partition, a recessed member carried by each of said conduits, an adjustable member hav-

ing its ends extending loosely into said recesses and adapted to be moved to alternately raise and lower said conduits, and means for automatically closing said conduits when 5 raised and opening the same when lowered.

9. A device of the class described, comprising a liquid holding tank having a partition therein, a pair of movable conduits extending into the tank upon opposite sides of 10 the partition, recessed members carried by each of said conduits, an adjustable member having its ends extending loosely into said recesses and adapted to alternately raise and lower said conduits, means for retaining said 15 adjustable member in each of its positions of adjustment, and means for automatically closing each of said conduits when raised and opening the same when lowered.

10. The combination with a suction producing 20 apparatus and a liquid fuel supply tank having a partition therein, conduits connecting said suction apparatus and said tank and extending into said tank on opposite sides of said partition, means for alternately raising and lowering said conduits, and means for automatically closing each of said 25 conduits when raised and opening the same when lowered.

11. The combination with a suction producing 30 apparatus and a plurality of liquid holding receptacles, conduits connecting said suction apparatus and said receptacles, means for alternately raising and lowering said conduits within said receptacles, means 35 for automatically closing each of said conduits when raised, said means co-operating with said receptacles to open said conduits when lowered.

12. The combination with a suction producing 40 apparatus, and a plurality of liquid holding receptacles, conduits connected with said apparatus and extending into said liquid holding receptacles, means for alternately raising and lowering said conduits 45 within said receptacles, and means for automatically closing and opening said conduits when raised and lowered.

13. The combination with the manifold and carburetor of an automobile engine, and 50 a pair of liquid holding receptacles, conduits adapted to project into said liquid holding receptacles, a gravity feed tank connected with said conduit and with said manifold and carburetor, means for simultaneously raising one and lowering the other of said 55 conduits within said receptacles, and means for automatically closing and opening said conduits when raised and lowered.

14. The combination with the manifold 60 and carburetor of an internal combustion engine, of a vacuum fuel tank, conduits connecting said manifold and carburetor with said vacuum fuel tank, a fuel supply tank having oppositely arranged fuel compartments, 65 movable connections leading from

said compartments to said vacuum fuel tank, and means serving to alternately open and close said connections when moved between certain predetermined limits.

15. The combination with the manifold 70 and carburetor of an internal combustion engine, of a vacuum fuel tank, conduits connecting said manifold and carburetor with said vacuum fuel tank, a fuel supply tank, shiftable connections interposed between 75 said vacuum and supply tanks each adapted to permit the flow of fuel from the supply tank to said vacuum tank when shifted to a predetermined position, and means adapted to alternately move said connections to said 80 positions.

16. The combination of a vacuum tank, a fuel supply tank, adjustable conduits between the same each adapted to permit the flow of fuel from the supply tank to the 85 vacuum tank when adjusted to a predetermined position, and means adapted to alternately move said conduits to said predetermined positions.

17. The combination of a vacuum tank, a fuel supply tank, adjustable conduits between the same adapted to alternately permit the flow of fuel from the supply tank to the vacuum tank, when adjusted to predetermined positions, and means for supporting 95 said conduits in said predetermined positions of adjustment.

18. The combination of a suction producing apparatus and a fuel supply tank, adjustable conduits between the same capable 100 of being moved between certain limits to permit fuel to alternately flow from said tank through said connections when in different positions of adjustment, and means adapted to support said conduits in said positions of 105 adjustment.

19. The combination of a suction producing apparatus and a fuel supply tank, adjustable conduits between the same each capable of being moved between certain limits 110 and through which fuel from the tank is adapted to alternately flow when said conduits are in their different positions of adjustment, and common means for effecting the adjustment of said conduits. 115

20. The combination of a suction producing apparatus and a fuel supply tank, adjustable connections between the same extending into the tank and capable of being moved between certain limits, valves upon 120 the connections adapted to be alternately opened and closed when the connections are adjusted between said limits, and means for effecting the adjustment of said connections.

21. The combination of a suction producing apparatus and a fuel supply tank, adjustable connections between the same extending into the tank and capable of being moved between certain limits, valves upon 125 the connections adapted to be alternately 130

- opened and closed when the connections are adjusted between said limits, and a member movable to simultaneously effect the adjustment of said connections.
5. 22. The combination of a suction producing apparatus and a fuel supply tank, adjustable connections between the same extending into the tank and capable of being raised and lowered therein, valves for each 10 of said connections adapted to be closed when the connection is in raised position and to be opened by contacting with the tank when the connection is lowered, and means for effecting the raising and lowering of 15 said connections.
23. The combination of a suction producing apparatus and a fuel supply tank, adjustable connections between the same extending into the tank and capable of being 20 raised and lowered therein, valves for each of said connections, springs for holding said valves closed when the connections are in raised position, said valves being held open by the tank when the connections are in 25 lowered position, and means for alternately raising and lowering the connections within the tank.
24. A device of the class described comprising a liquid holding tank, a pair of relatively 30 movable outlet conduits adjustable within the tank, means adapted to alternately raise and lower said conduits, and means for automatically closing and opening said conduits when raised and lowered.
35. 25. A device of the class described comprising a liquid holding tank, a pair of relatively movable discharge members adjustable within the tank, and means adapted to alternately open and close said discharge 40 members when moved to different positions of adjustment.
26. A device of the class described comprising a liquid holding tank, a pair of relatively movable discharge members adjustable within the tank, common means for actuating said members, and means adapted to alternately open and close said discharge members when moved to different positions of adjustment.
5. 27. A device of the class described comprising a liquid holding tank, a pair of relatively movable discharge members adjustable within the tank, common means for actuating said members, and a spring pressed valve for each of the members serving to close the same when in one position of adjustment and co-operating with the tank to open said member when in another position of adjustment.
28. In a device of the class described, a pair of liquid holding receptacles, a conduit extending into each of said receptacles, means for lowering said conduits alternately and means dependent upon the position of said conduits for controlling the flow of liquid therethrough.
29. In a device of the class described, a pair of liquid holding receptacles, a conduit extending into each of said receptacles, means dependent upon the position of each of said conduits for controlling the flow of liquid therethrough and means for simultaneously shifting said conduits in opposite directions.
30. In a device of the class described, a pair of liquid holding receptacles, a conduit extending into each of said receptacles and adapted to be raised and lowered, valve means for opening each of said conduits when said conduit is in its lowered position and means for alternately lowering said conduits.

In testimony whereof, we affix our signatures.

CHARLES F. GREEN.
HARRY W. LINDSEY, JR.
